AUTOMOBILE REARVIEW MIRROR

Dwight M. Nelson, Chicago, Ill., assignor to
Nelmor Corporation, a corporation of Illinois

Application December 13, 1951, Serial No. 17,716

Term of patent 14 years

(Cl. D14--6)

To all whom it may concern:

Be it known that I, Dwight N. Nelson, a citizen of the United States, residing at Chicago, county of Cook, and State of Illinois, have invented a new, original, and ornamental Design for an Automobile Rear View Mirror, of which the following is a specification, reference being had to the accompanying drawing, forming a part hereof.

Fig. 1 is a perspective view of an automobile rear view mirror, showing my new design.

Fig. 2 is a top plan view thereof.

Fig. 3 is a rear elevational view thereof.

The face view of the mirror glass is conventional in appearance.

I claim:

The ornamental design for an automobile rear view mirror, as shown and described.

DWIGHT M. NELSON.
